UNITED STATES PATENT OFFICE.

ANTHONY ABEL, OF NEW YORK, N. Y.

DESIGN FOR BARBER'S CHAIR.

Specification forming part of Design No. **7,168**, dated February 17, 1874; application filed January 17, 1874.
[Term of Patent 3½ years.]

To all whom it may concern:

Be it known that I, ANTHONY ABEL, of the city, county, and State of New York, have invented a new and original Design for Barber's Chair, of which the following is a specification:

The nature of my design is fully represented in the accompanying photographic illustrations, to which reference is made.

a is the adjustable head-rest. *b* is the back; *c*, the arms; *d*, the seat. The arms and back rest on supports, consisting of figures *e*, representing the neck, *f*, head, *g*, and wings, *h*, of

birds and animals. The seat is supported on sides *i i*, formed of corner-legs *j*, terminating in heads *k*, with intervening curved or scroll ornamental work *l*.

I claim as my invention—

A design for a barber's chair, substantially as shown and described.

ANTHONY ABEL.
